APPARATUS FOR THE PRODUCTION OF
COKE AND GAS IN HORIZONTAL CHAM-
BER OVENS

Carl Still, Recklinghausen, Germany

Application June 12, 1931, Serial No. 543,960
In Germany June 19, 1930

2 Claims. (Cl. 202—257)

The object of the apparatus described below is to provide means, in horizontal chamber ovens for the production of coke and gas, by which an easy and rapid withdrawal of the gases and 5 vapours of distillation from a charge of coke is effected during the gasification and coking, and by which also the products of distillation and coking are improved both as regards their value and yield, and the working of the oven is facilitated.

The accompanying drawing, which illustrates the new apparatus, is a vertical longitudinal section taken through the centre of an oven chamber in the condition in which it has been freshly 15 charged with coking coal.

The oven chamber, which in the usual manner is heated from both side walls, is bounded above by a brickwork roof *a*, below by the sole *b*, and at the front and back by the doors *c* and *d*. 20 In the oven chamber there is a charge *f* of coal, the surface *h* of which is made horizontal by the usual levelling means, a free gas collecting space *g* being left between this surface and the arch of the oven roof *a*.

25 Five charging openings *i*, distributed over the whole length of the chamber, are provided in the oven roof *a*. At the right-hand end of the chamber there is a gas withdrawal opening *m* on which is an ascension pipe *n* connected to a gas and tar main *v*. Also, according to the invention, by the side of and between the charging openings *i* in the oven roof *a* there is a suitable number, according to the example illustrated six, of narrow openings or passages *k* passing through 30 the roof *a*. All these passages *k* are connected by lateral tubulures *o* with a gas collecting pipe *p* disposed in the oven roof, and connected over a closing device *q* to a second gas and tar main *w*.

The buckstays *r* are extended upwards for a 40 certain distance over the oven roof at both sides of the oven, and carry at their upper ends a pair of rails *s* which form a running track for an apparatus *t* constructed as a traveller. A shaft *j*, parallel to the longitudinal axis of the oven 45 chamber and supported on the traveller *t*, is provided at its left-hand end with a suitable driving apparatus (for example a motor) and carries six winding drums *u* disposed vertically over the openings *k* of the roof *a*. Tubes *x* or *l* or solid rods *y* are suspended by cords *z* wound on the drums *u* in such a manner that they can pass through the passages *k* into the oven chamber and be inserted into or withdrawn from the charge *f* of coal. These tubes *x*, *l* or rods *y*, 50 which are preferably pointed at their lower end,

act as formers by means of which channels or ducts *e* can be made in the interior of the charge *f*. In the drawing, for the purpose of explaining the working, several tubes *x*, *x'*, *l* and rods *y* are represented at different heights as suspended from the cords *z* or inserted in the coal charge *f*; practically, however, the arrangement would usually be such that all the forming bodies were suspended at the same level and inserted simultaneously into the oven chamber and withdrawn 10 together from it.

The working of the described arrangement can, for example, be as follows: when the coke formed from the previous charge has been removed, and the doors *c* and *d* have been inserted, the coal is 15 dropped loosely in the usual manner into the chamber through the charging openings *i* of the roof *a* and is levelled from the door *d* which is provided with an opening for this purpose, so that the mass *f* of the coal has a horizontal 20 surface *h*.

The forming bodies *x*, *l*, *y*, suspended on the cords *z*, are inserted by the winding drums *u* on the apparatus *t* through the openings *k* in the roof into the oven chamber and into the mass *f* 25 of coal, so that vertical ducts *e* extending approximately over the whole height of the charge to the surface *h* are formed in the coal. The formers *x*, *l*, *y* are then raised and removed entirely from the chamber.

The formers can be removed directly after their insertion if the ducts *e*, as soon as they are formed, are sufficiently consolidated so as to remain without danger of collapsing after the removal of the formers. In this case the solid rods 35 *y* can be used as the formers. If, however, the ducts *e* cannot be relied on with certainty to maintain their form, and only acquire sufficient rigidity after the gasification and coking process has proceeded to a certain stage, it is advisable 40 to employ as the formers tubes *x* which remain for a certain time in the ducts; in order that in this position they should not hinder the flow of the gases and vapours their walls are provided with perforations distributed over the whole of 45 the length projecting into the oven chamber. A tube of this kind remaining temporarily in the oven chamber or the charge *f* of coal is represented in the drawing at *x'* and *l*.

It is obvious that the perforations in the tubes 50 enable the gases and vapours within the charge of coal and the oven chamber to flow freely as in empty duct *e*. Also it is not necessary, as shown with the tube *x'*, that such a tube should pass through the free gas collecting space *g* and there- 55

by connecting the duct *e* formed by it with the opening *k* in the roof above it; it is, on the other hand, sufficient if the tube has only a length such that its upper end extends to the surface *h* of the charge *f* of coal, as illustrated in the drawing with the tube *l*. The withdrawal of the tube *x* is facilitated if, as shown in the drawing in the case of the tube *x'*, its lower end is upset into a slightly larger and rounded form, so as to produce a duct of somewhat larger diameter than that of the body of the tube, since in this way the external surface of the tube is not jammed by the surrounding mass of coal.

It is obvious that in the described method of working, if required, the charging openings *i* of the oven roof *a* can be utilized for the insertion of the formers *x*, *l*, *y* as well as the openings *k* in the roof provided especially for this purpose, or only the charging openings *i* may be provided 20 and the openings *k* omitted.

If separate charging openings *i* are provided, in addition to the openings *k* in the roof, for the introduction of the formers *x*, *l*, *y*, the formers *x*, *l*, *y* can be introduced through the openings *k* 25 in the roof into the oven chamber until they are at their lowest positions, and the coal can then be dropped through the openings *i* into the chamber, and then finally the formers *x*, *l*, *y* withdrawn upwards, leaving the ducts *e* in the mass *f* of the 30 coal. Also in this case obviously the formers can be withdrawn directly or, when perforated tubes are used, at a later stage. The levelling of the coal in this method of working, since it must be effected after the introduction and before the removal of the formers, requires special 35 precautions in order that the levelling tools and the inserted formers should not mutually interfere.

When the formers *x*, *l*, *y* have been removed 40 from the chamber after the ducts have been formed and all the openings *k* and *i* in the roof have been closed by plugs or covers, the gases and vapours of distillation can be drawn off from the oven chamber.

45 When the collecting pipe *p* is provided, as described, the openings or passages *k* in the roof can be used for drawing off the gases and vapours of distillation from the gas collecting space *g*. In this case the gases and vapours emanating 50 through and from each of the ducts *e* are drawn off directly, along the shortest way, into a passage *k* situated immediately above and pass then into the gas and tar main *w*. If the gas and tar main *v*, with the ascension pipe *n*, is provided as described, the gases and vapours of distillation can 55 also be drawn off through the opening *m* in the roof into the gas and tar main *v* either exclusively in this path, in which case the collecting pipe *p* and the gas and tar main *w* are no longer required, or in conjunction with the described withdrawal through this collecting pipe *p* into the 60 gas and tar main *w*. When both containers *v* and *w* are provided, it is preferable to utilize the container *w* in the first stage of the gasification and coking process in which mainly cooler 65 gases and vapours are developed, and then to shut off this gas and tar main *w* by means of the valve *q*, and in the next succeeding second stage to use the gas and tar main *v*, which up 70 to that time has been closed, for drawing off the later developed and considerably hotter gases and vapours.

The ducts *e* formed by the described apparatus in the interior of the charge *f* of coal provide 75 the quickest and shortest path for the flow of

the volatile products of distillation formed during the gasification and coking. In this way the freshly developed volatile constituents are prevented from flowing towards the heated walls of the chamber and from being decomposed as they 5 pass along these highly heated surfaces, as it is the case in the usual manner of working. In this usual method, direct losses also occur in these volatile constituents by the fact that the charge of coal adhering closely to the walls of 10 the chamber, at least in the initial stage in which no fissures or cracks have been formed in the coke by shrinkage, obstructs the flow of gases and vapours along the walls, so that the freshly 15 produced gases and vapours of distillation are liable to pass through the chamber walls, which are never entirely gas-tight, into the heating flues. These losses in the products of distillation are excluded by the arrangement according to the invention. By avoiding the drawbacks occurring in the usual method of working, the quality and yield of the by-products of the distillation of the coal are improved. The tar contains more valuable constituents of low boiling point and a smaller admixture of less valuable constituents of high boiling point of pitch-like character.

Since the volatile products of distillation can flow in the direction from the heated walls of the chamber towards the ducts disposed in the 30 centre of the charge of coal, the heat transmission from the walls of the chamber into the mass of coal is increased and facilitated. In this way the process of distillation is accelerated and less heat wasted. At the same time, by 35 avoiding the concentration of heat and overheating, the production of coke in large pieces of exceptionally good quality is ensured. Since the freshly developed gases and vapours of distillation are led away from the walls of the chamber, 40 deposition of graphite, due to decomposition of the gases, on the walls is avoided or at least reduced, an advantage which is more particularly of importance in modern chamber ovens with highly intensive heating.

It is not absolutely necessary that the ducts *e*, 45 as shown in the example of the drawing, should form a single row in the central plane of the coal cake; they may be distributed in several rows or in other arrangements between the 50 bounding sides of the mass of the coal.

Having thus described the nature of the said invention and the best means I know of carrying the same into practical effect, I claim:—

1. The combination of an oven having a horizontal chamber for the distillation of coal including a roof having spaced passages in the central longitudinal plane of the chamber passing substantially vertically through said roof, and a mechanism for forming ducts in a charge with- 55 in the oven chamber comprising a track disposed over each end of said chamber in a direction transverse to the longitudinal axis thereof, a carriage on said tracks adapted to be brought into the central longitudinal plane of the chamber, 60 a plurality of mutually independent elongated duct forming tools adapted to pass through said passages, duct tool operating means for each of said tools of the plurality carried by said carriage and spaced along its length to register with 65 said passages, and means for independently operatively connecting each of said duct forming tools with its respective operating means whereby the tools may be moved vertically into and out of said chamber through said passages for the 70 75

purpose of forming ducts within a body of coal charged into said chamber.

2. The combination of an oven having a horizontal chamber for the destructive distillation of coal including a roof having spaced passages in the central longitudinal plane of the chamber passing substantially vertically through said roof, and a mechanism for forming ducts in a charge within the oven comprising a frame at each end of said oven extending above the roof thereof, a track supported on the upper extremity of said frame and disposed transversely to the longitudi-

dinal axis of said oven, a carriage adapted to move along said tracks, elongated duct forming tools adapted to pass through said passages, winding drums on said carriage adapted to be positioned over said passages, cables attached to the upper end of said tools and to said drums, means for simultaneously rotating said drums for moving said tools vertically into and out of said chamber through said passages for the purpose of forming ducts within a body of coal charged into said chamber. 5 10
